(57) **CLAIM**

The ornamental design for a floral delivery container, as shown and described.

DESCRIPTION

FIG. 1 is a front perspective view of a delivery container with a sliding inner base in a protruding position;

FIG. 2 is a front perspective view of a delivery container with the sliding inner base in an enclosed position;

FIG. 3 is a right-side view of the delivery container of FIG. 2;

FIG. 4 is a left-side view of the delivery container of FIG. 2;

FIG. 5 is a front view of the delivery container of FIG. 2;

FIG. 6 is a rear view of the delivery container of FIG. 2;

FIG. 7 is a top view of the delivery container of FIG. 2;

FIG. 8 is a bottom view of the delivery container of FIG. 2; and,

FIG. 9 is a top cross-sectional view of the delivery container of FIG. 1.

In the drawings, the broken lines depict unclaimed subject matter only and form no part of the claimed design.
